CONTAINER

William Edward Taylor, Fairfield, Conn., assignor to American Can Company, New York, N.Y., a corporation of New Jersey

Filed Dec. 28, 1962, Ser. No. 247,983
11 Claims. (Cl. 220—53)

This invention relates to hermetically sealed cans or containers which may be readily opened without the use of an opening key or other opening tool and has particular reference to a can having a friction closure which is sealed in place by a thin flexible sealing ring which may be easily peeled from the can to permit removal of the closure.

There is today in the packaging field a definite desire for a hermetically sealed, tamperproof can which can be easily opened without recourse to tools such as can openers or opening keys.

The present invention contemplates the fulfillment of this desire by providing a can having a friction closure which is formed with a top panel having a smooth, outer edge portion which is in substantial horizontal alignment with the smooth, inner edge portion of the friction ring in which the closure is seated, these smooth, adjacent edge portions of the closure and the ring in which it seats cooperatively combining to create a smooth continuous surface which provides a seat for a thin, adhesively sealed, peelable sealing ring which bridges the area of frictional contact between the closure and the ring to provide a tamperproof, hermetic seal for the can. In order to provide for removal of the sealing ring, it is formed with a projecting pull tab which permits the consumer to easily strip the ring from its seat to thereby release the friction closure, which thereafter serves as a reclosure for the can.

An object of the present invention, therefore, is the provision of a hermetically sealed container which may be readily opened without the use of an opening key or other tool by merely peeling off a sealing ring.

Another object is the provision of a friction reclosure can provided with a readily peelable sealing ring which forms a seal which is gas-tight and is also resistant to blow-off pressure so that the can may be used for preserving food products under either vacuum or pressure.

A further object is the provision of a can which is tamperproof, attractive in appearance, easily opened, and provided with a smooth edge friction reclosure member.

Numerous other objects and advantages of the invention will be apparent as it is better understood from the following description, which, taken in connection with the accompanying drawings, discloses a preferred embodiment thereof.

Referring to the drawings:

FIGURE 1 is a top plan view of a sealed container embodying the present invention;

FIG. 2 is a vertical sectional view of the upper part of the instant container drawn to an enlarged scale, the view being taken along the line 2—2 in FIG. 1;

FIG. 3 is a fragmentary top plan view showing a modified form of the invention on the container shown in FIG. 1; and

FIG. 4 is a fragmentary vertical sectional view of the upper part of the container shown in FIG. 3, drawn to an enlarged scale, the view being taken along the line 4—4 in FIG. 3.

As a preferred or exemplary embodiment of the invention, FIGS. 1 and 2 of the drawings illustrate a

2

cylindrical can which may be formed of thin sheet metal such as tin plate, aluminum plate, or the like. The can includes a tubular body 12 which is closed and sealed at its bottom end by a conventional double seamed bottom member, which is not shown.

The body 12 is closed at its upper end by a friction ring 13 and a friction closure 14 which is frictionally seated therein. The marginal edge portion of the friction ring 13 preferably is interlocked with the upper end of the can body 12 in a conventional hermetic double seam 15. The closure ring 13 (FIG. 2) also comprises a countersink wall 16 which forms the innermost layer of the double seam 15, an inwardly extending smooth annular step wall 17, a depending vertical friction wall 18, and an inwardly extending annular horizontal flange 19, the inner edge of which is reversely bent in a hem 20 and defines a central opening 21 through which the can may be filled or emptied.

The friction closure 14 (FIG. 2) preferably is formed from a flat metal blank, and comprises a flat annular panel 25 having an outer marginal edge portion which is bent downwardly into a peripheral depending friction wall 26 which frictionally engages the annular friction wall 18 of the friction ring 13 for frictionally retaining the closure 14 in position in the friction ring 13. At the lower end of the friction wall 26, the terminal edge portion of the closure 14 is bent inwardly and upwardly into a hollow curl 27 which provides a smooth, relatively rigid reinforced outer edge for the reclosure 14.

In order to facilitate the application of the closure 14 into seated position in the friction ring 13 and to permit its removal therefrom, the reclosure 14 is provided with a raised finger engaging knob 28 which is located central of the panel 25 and which preferably does not extend above the top edge of the top double seam 15.

The friction closure 14, when in closed position in the friction ring 13 (FIG. 2), is disposed in a recess or seat 30 which is defined by the friction wall 18 and the surrounding annular flange 19. The depth of the seat 30 preferably is such that the upper surface of the step wall 17 of the friction ring 13 is in the same plane as the upper surface of the annular panel 25 of the friction closure 14 (FIG. 2), thus providing a substantially continuous, flush annular sealing surface, generally designated by the numeral 31 which includes the adjacent annular surfaces of the step 17 and the panel 25.

The can is hermetically sealed by means of a tamperproof annular sealing ring 32 which is adhesively secured to the flush sealing surface 31 of the can in such manner that it bridges the friction ring 13 and the friction closure 14 and is sealed to both of these parts to form a hermetic liquidproof seal which completely seals the can and prevents any leakage of any fluid between the friction walls 18 and 26.

As exemplary of a suitable sealing ring construction, the drawings disclose it as being formed of a laminate material which comprises an upper layer 33 formed of a thin flexible metal foil such as aluminum foil and a bottom layer 34 formed of a thin film of a suitable thermoplastic resin which is heat sealed to the sealing surface 31 and which is sufficiently low in peel resistance to permit it to be stripped cleanly from the sealing surface 31 without requiring the use of opening tools of any type.

The layer 34 comprises a random copolymer of ethylene and acrylic acid having a copolymerized acrylic acid content in the neighborhood of 3% (plus or minus 0.5% by weight, based on copolymer weight, and a melt index of 8, plus or minus 1.

en measured at 23° C., this material has the following approximate physical properties:

y	.923
pe strength	1720 p.s.i.
e impact	1500 p.s.i.
strength	1345 p.s.i.
ation	520 percent
ty	1.5×10^4 p.s.i.
ess (Shore C)	80

1 tests with this ethylene-acrylic acid copolymer in two strips of tin plate, each $\frac{3}{4}$ " wide, which are 20 glued to each other by an interposed layer of this 25 copolymer are pulled apart at an 180° angle at a speed of 30 per minute and a temperature of 77° F. indicate 35 strength of about 2.4 lbs. per $\frac{3}{4}$ lineal inch.

1 resin is particularly desirable since it is impervious 20 water, grease, and all other fluids to which the 25 exterior and interior of the can 10 is normally exposed, has 30 sired low peel strength, and forms a self-sustaining 35 which strengthens the aluminum foil layer.

1 ethylene-acrylic acid copolymer is preferably 20 extruded onto the aluminum foil layer 33 while in a 25 state. The most practical way of accomplishing 30 to extrude the resin onto a large web or sheet of 35 aluminum foil and to then cut the sealing ring 32 from 40 sultant aluminum foil-resin lamination. It has 45 found that a sealing ring 32 of sufficient strength and 50 ability to meet the normal requirements of the instant 55 can is produced when the aluminum foil layer 33 is 0.003 inch thick and the resin layer 34 is about 3 60 mic. These thicknesses can of course be varied to 65 specific can requirements.

1 will be understood that adhesive materials differing 20 in position from the above described thermoplastic 25 may be utilized as the layer 34. The particular 30 com- 35 a used will depend to great extent on the particular 40 requirements.

1 der to provide for easy opening of the can without 20 of an opening key or other tool, a pull tab 35 is 40 ad (see FIG. 1), which is not adhered to the under- 45 panel wall 25. The pull tab 35 is formed as an in- 50 part of the sealing ring 32 and extends angularly 55 from the inner periphery of the sealing ring 32 60 along a chordal center line so that when the pull tab 35 65 is pulled upwardly and circumferentially around 70 of the can, the sealing ring 32 is torn across, along 75 a line which is generally indicated by the dot 80 line 36 in FIG. 1, and then stripped from the 85 surface 31 in a clockwise direction, as indicated 90 arrow in FIG. 1.

1 tearing across of the sealing ring 32 is facilitated 20 configuration of the pull tab 35, as viewed in FIG. 25. One of the side edges of this pull tab 35 and the 30 peripheral edge of the sealing ring 31 define an acute 35 angle which serves to initiate the tear in such manner 40 as directed across the sealing ring 32. It is obvious 45 that other shapes of pull tabs may be used, and that the 50 ring 32 may be partially slit, or provided with a 55 perforations which extend partially or completely 60 across line 36 to more positively direct the tear across 65 ring 32.

1 the sealing ring 32 has been peeled off, the friction 20 closure 14 may be removed to permit removal of part or 25 the container contents. If all of the contents are not 30 immediately, the closure 14 thereafter may be 35 repositioned on the can for the purpose of 40 protecting the remaining portion of the 45

1 modified form of the invention, FIGS. 3 and 4 of 20 vings illustrate a can which is designed to withstand 25 greater internal pressures than can be contained by 30 a can of FIGS. 1-2. For this purpose, annular 35 wall 17 is inclined upwardly to give it a frusto-conical 40 configuration so that when the closure 14 is urged upward- 45

5 ly by internal pressure great enough to overcome the friction between the friction walls 18 and 26, the conically disposed adhesive bond between the sealing ring 32 and the step wall 17 will be subjected to more of a shearing stress and less of a peeling stress than in the form of the invention disclosed in FIGS. 1 and 2. Thus, because the bond between the thermoplastic resin 34 and the sealing surface 31 is much more resistant to shearing stresses than to peeling 10 stresses, the can of FIGS. 3 and 4 is capable of holding higher internal pressures than is the can of FIGS. 1 and 2. It will be noted, however, that even in FIGS. 3 and 4, the panel 25 of the friction closure forms a smooth 15 continuation of the step wall 17, and the two still combine to provide a sealing surface 31 for the reception of the sealing ring.

1 The can of FIGS. 3 and 4 also differs from that of 20 FIGS. 1 and 2 in that the sealing ring 32 is provided with 25 a free, non-adhered pull tab 38 which extends from the 30 outer peripheral edge of the sealing ring 32 and is 35 reversely folded back over the ring so that it extends radially 40 of the can.

1 In this modified form, the sealing ring 32 may be easily 20 removed by merely lifting the pull tab 38 upwardly and 25 thereafter peeling off the sealing ring 32 from its sealed 30 position on the upwardly sloping step wall 17 and the 35 substantially flat panel wall 25 of the reclosure 14. In 40 this peeling operation, the sealing ring 32 is not torn across, as in FIGS. 1 and 2, but instead the peeling action begins at the pull tab 38 and progresses around the top 45 of the can in both directions, as indicated by the arrows in FIG. 3. All other parts of this modified form of 50 instant container not herein differentiated are substantially 55 identical to the parts hereinbefore described in connection with the preferred embodiment of this invention.

1 It is thought that the invention and many of its attendant 20 advantages will be understood from the foregoing 25 description and it will be apparent that various changes 30 may be made in the form, construction and arrangement 35 of the parts without departing from the spirit and scope 40 of the invention or sacrificing all of its material advantages, the form hereinbefore described being merely a 45 preferred embodiment thereof.

I claim:

1. A hermetically sealed container comprising a tubular 20 body, a ring secured to an end of said body, said ring 25 comprising an annular wall and a recessed annular seat, a closure disposed in said seat and having a substantially 30 horizontal annular wall which is substantially flush with the adjoining inner edge portion of said annular ring 35 wall and disposed radially inwardly thereof, and a peelable 40 annular sealing member bridging and adhesively bonded to adjoining portions of said annular ring wall and said annular closure wall to provide a hermetic, tamper-proof seal for said container.

2. The container of claim 1, wherein said sealing member 20 comprises an annular flexible sealing ring which is 25 bonded to said adjoining portions of said annular ring 30 wall and said annular closure wall by an adhesive which 35 has low peel resistance.

3. The container of claim 2 wherein said annular sealing 25 ring comprises a layer of flexible aluminum foil and 30 a layer of an adhesive.

4. The container of claim 3 wherein said adhesive 20 comprises a layer of a thermoplastic resin which is heat sealed 25 to said ring and closure.

5. The container of claim 4 wherein said thermoplastic 20 resin comprises a copolymer of ethylene and acrylic acid.

6. A hermetically sealed container comprising a tubular 20 body, a friction ring secured to an end of said body, 25 said ring comprising an annular substantially horizontal 30 wall and a vertical friction wall, a friction closure for 35 said container, said closure having a peripheral friction 40 wall which is frictionally engageable with the vertical 45 friction wall of said ring for retaining said closure in 50 closed position on said friction ring, said closure also hav- 55

ing an annular wall portion which is substantially flush with the adjacent inner edge portion of said annular ring wall, an annular sealing ring bonded to adjoining portions of said annular ring wall and said annular closure wall by an adhesive which has low peel resistance, and a pull tab extending from said sealing ring to facilitate the peeling of said sealing ring from said adjoining ring and closure portions.

7. The container of claim 6 wherein the annular wall of said friction ring inclines upwardly and inwardly.

8. The container of claim 6 wherein said closure includes finger engaging means which extend above said annular closure wall within said annular sealing ring to facilitate handling of said closure.

9. The container of claim 6 wherein said pull tab

extends from the outer periphery of said annular seal ring.

10. The container of claim 6 wherein said pull extends from the inner periphery of said annular seal ring.

11. The container of claim 10 wherein said pull extends angularly from said sealing ring.
